UNITED STATES PATENT OFFICE.

PETER J. COPPENS, OF GRAND RAPIDS, MICHIGAN.

HEATING-STOVE.

SPECIFICATION forming part of Letters Patent No. 755,277, dated March 22, 1904.

Application filed September 24, 1903. Serial No. 174,459. (No model.)

To all whom it may concern:

Be it known that I, PETER J. COPPENS, a citizen of the United States, residing at Grand Rapids, in the county of Kent and State of Michigan, have invented certain new and useful Improvements in Heating-Stoves; and I do hereby declare the following to be a full, clear, and exact description of the invention, such as will enable others skilled in the art to 10 which it appertains to make and use the same.

My invention relates to improvements in heating-stoves; and its object is to provide the same with certain features, and more particularly to that class of stoves having detachable internal parts and adapted to operate with or without the same to readily remove and insert the detachable parts, whereby the stove is adapted to burn a great variety of fuel and to burn soft coal and like materials 15

20 without smoke or waste, and to provide the device with certain new and useful features hereinafter more fully described, and particularly pointed out in the claims.

My invention consists, essentially, in certain 25 modifications of fire-pot construction, together with internal attachments of peculiar construction, and adapted to be readily removed or placed in position within the stove, as will hereinafter more fully appear by reference to the accompanying drawings, in which—

Figure 1 is a vertical section of a stove embodying my invention, taken on the line 1 1 of Fig. 2 and with the base of the stove omitted; Fig. 2, a horizontal section of the 35 same on the line 2 2 of Fig. 1; Fig. 3, a plan view of the same with the outer cover J' removed, and Fig. 4 a horizontal section of the fire-pot on the line 4 4 of Fig. 1.

Like letters refer to like parts in all of the 40 figures.

A represents the fire-pot, having the usual truncated conical shape and provided with an air-chamber B in the upper part thereof and inlet-openings B' to permit air to escape from 45 said air-chamber over the top of the fire.

C is a suitable cold-air inlet to said air-chamber, and extending downward on the 50 outside of the fire-pot are any convenient number of air-passages, (preferably three, as shown,) which passages connect the base with

the chamber B and supply the said chamber with hot air when the inlet C is closed. The openings B' extend only through the front part of the fire-pot, and the two front air-passages D have slots or openings E opening into the fire-pot and extending upward into the chamber B, whereby the air is supplied to the front part of the fire-pot from both the chamber B and the passages D. The rear passage D has small openings E' near the bottom 60 only and is otherwise closed off from the fire-pot. The air-supply is thus limited to the front portion of the fire-pot and to the lower rear part thereof, the upper rear portion of the fire-pot being without air-supply. 65

F represents the body of the stove, preferably of the usual cylindrical form and having the usual front door F' and a top having an opening closed by the outer cover J'.

The device so far described thus constitutes a 70 complete wood-burning stove having a fire-pot modified and adapted to coöperate with the attachments G, H, and I, hereinafter described, which when inserted adapt the stove to operate as a coal-burner having certain 75 novel features of construction and operation whereby the fuel is burned at the front part only and the hot gases therefrom pass all round the magazine and heat the entire body F.

Above the upper rear portion of the fire-pot 80 and with its lower rim engaging the top of the rear portion of the fire-pot and open at the front side for the escape of gases and flames of combustion is a detachable coking-chamber G, having a thickened front wall G' extending across from side to side of the upper part of the fire-pot, thus leaving a crescent-shaped opening between the chamber G and the front of the stove. This chamber engages the fire-pot throughout about one-half of the 85 circumference thereof, whereby it is securely supported without fastenings or other support. Above this coking-chamber is a magazine H, extending to near the top of the stove and terminating in a funnel-shaped portion I, 90 having a flange at the top suitably connected to the top of the stove. This magazine is preferably truncated conical in form, having its small end upward to prevent clogging of the fuel therein, and the funnel I is flanged to fit 95 100

the opening in the top. The parts G, H, and I thus constructed and arranged will be securely held in place without bolts, rivets, or other fastenings and are readily removed or replaced without need of tools of any kind. Within the upper portion I is a lid or hinged cover J, to be opened when fuel is to be supplied to the magazine and located somewhat below the top of the funnel I. Covering the opening of the funnel is an outer cover J'. These two covers J and J' are thus spaced apart, and a chamber is thus formed between them from which is an opening K for the escape into the stove of any gases that may accumulate in said chamber. The part I is readily removed by lifting the same upward, and the parts H and G can then be taken out through the front opening of the door F'. These attachments thus are removable through the usual openings without tools and without taking apart of any portion of the stove and when in use are securely supported in place by the fire-pot and top of the stove. When the parts G, H, and I are removed, the remaining stove is then well adapted for burning wood or other like fuel. The parts G, H, and I can also be readily and quickly placed within the stove through the usual top and front openings, and when placed therein they provide the same with a magazine and coking-chamber of peculiar construction and adapted to coöperate with the fire-pot, whereby the stove is adapted to burn either hard coal, soft coal, or slack, and the soft coal or slack will be readily burned without producing smoke, and the combustion will be very complete and economical, the operation being as follows: The fuel is heated in the magazine H and coking-chamber G and also in the rear upper portion of the fire-pot, and by this heating the volatile portions are driven off and escaping forward beneath the front portion G' of the coking-chamber G are there supplied with sufficient hot air escaping through the openings E and B' to produce a clear blue flame and complete combustion. By the time the fuel has settled down and passed into the front portion of the fire-pot, where it becomes incandescent and finally consumed, the said fuel has become so thoroughly coked that it will then give off no unconsumed carbon or smoke.

The device is also obviously well adapted for burning hard coal, the consumption of the gases being complete and without any wasteful escape of partially-consumed gas. In the event that the stove is used for wood or other like fuel the parts G, H, and I are easily and quickly removed for that purpose and again replaced for burning hard or soft coal. I thus secure a practical and efficient stove for a great variety of fuels.

Having thus fully described my invention, what I claim, and desire to secure by Letters Patent, is—

65 1. In combination with a stove having a fire-

pot, a body above the fire-pot, and a top to the body having an opening and a cover; a coking-chamber, a magazine and a funnel extending continuously from the opening in said top to the fire-pot, and detachably supported in place solely by the fire-pot and top.

2. In combination with a wood-burning stove comprising a fire-pot, a body above the fire-pot provided with a front door, and a top having an opening and a cover; a removable coal-burning attachment of tubular form, and engaging the top of the fire-pot at the rear and sides thereof, and extending continuously from the fire-pot to the opening in the top, and supported in place solely by the top and fire-pot. 80

3. In combination with a stove having a fire-pot, a body having a front opening, and a top having a top opening, detachable parts supported in place solely by the fire-pot and top and comprising a funnel-section removable through the top opening, a magazine removable through the front opening, and a coking-chamber also removable through the said front opening. 85

4. In a stove, a truncated conical fire-pot having an air-chamber in its upper portion, openings from said air-chamber into the front portion only of the fire-pot, an inlet to admit cold air to said air-chamber, two vertical air-passages near the front of the fire-pot and extending from the base of the stove to the air-chamber, vertical slots connecting the said passages with the interior of the fire-pot, a vertical passage at the rear of the fire-pot and connecting the air-chamber and base of the stove, and openings from said passage into the fire-pot near the bottom thereof. 90

5. In combination with a wood-burning stove, comprising a fire-pot, a cylindrical body above the fire-pot and having a front door, and a top having an opening and a cover for said opening; a coking-chamber resting upon the fire-pot and disconnected therefrom at the front only, a magazine above the coking-chamber and having an opening into the interior of the stove and a flange connecting it to the top, and an inner cover in the magazine and below said opening. 105

6. In combination with a wood-burning stove, comprising a fire-pot, a body having a front door and a top having an opening and a cover; a removable coal-burning attachment comprising a coking-chamber adapted to rest upon the fire-pot at the rear thereof and supported thereby, a truncated conical magazine adapted to rest upon the coking-chamber, and a funnel-section adapted to rest upon the magazine and to fit within the opening of the top and having an opening into the body of the stove, and an inner cover below the said opening. 110

7. In a wood-burning stove, the combination of a top having an opening and a cover, a body having a front door, a fire-pot having an air-chamber, and vertical flues, and openings from the air-chamber and flue at the front side of 115

the fire-pot only, and a detachable coal-burning attachment comprising a tubular structure extending continuously from the fire-pot to the opening in the top, and disconnected from the fire-pot at the front only.

8. The combination of a fire-pot having an annular air-chamber at the top, means for admitting cold air to said air-chamber, air-passages near the front of the fire-pot connecting said chamber with the base of the stove, slots connecting said chamber and passages with the interior of the fire-pot at the front portion only thereof, a removable coking-chamber resting on the fire-pot at the rear portion there-

of and having a thickened front portion extending across above the fire-pot and opposite said air-openings, a magazine above the coking-chamber, a funnel-top to the magazine, two closures to said top and spaced apart, and an opening between said closures for the escape of gases.

In testimony whereof I affix my signature in presence of two witnesses.

PETER J. COPPENS.
